UNITED STATES PATENT OFFICE.

ALFRED A. O. SEEGER, OF SOUTH ORANGE, NEW JERSEY.

KEY HOLDER.

Application filed December 31, 1924. Serial No. 759,144.

To all whom it may concern:

Be it known that I, ALFRED A. O. SEEGER, a citizen of the United States of America, and resident of South Orange, in the county 5 of Essex and State of New Jersey, have invented a new and Improved Key Holder, of which the following is a full, clear, and exact description.

This invention pertains to holders and has 10 particularly reference to a holder for keys.

The invention primarily comprehends a key holding device which is particularly designed as a medium for the reception of the keys to a motor car whereby the same 15 may be completely covered and housed when not in use and whereby the same may be readily swung from a position within the holder for use.

The invention furthermore contemplates 20 a key holder which conforms generally to the shape of the keys which it receives and which is so designed as to frictionally maintain the keys either in a housed position or in a projected position for use.

25 As a further object the invention provides an improved key holder which facilitates the application or removal of the keys.

The invention furthermore resides in the 30 provision of a key holding device which is extremely simple in its construction, inexpensive to manufacture and produce, which is highly effective in its appearance and efficient for the purpose for which it is intended.

35 With the above recited and other objects in view, the invention resides in the novel construction set forth in the following specification, particularly pointed out in the appended claims and illustrated in the accompanying drawings, it being understood that 40 the right is reserved to embodiments other than those actually illustrated herein, to the full extent indicated by the general meaning of the terms in which the claims are expressed.

45 In the drawings:—

Figure 1 is a perspective view of the key holding device illustrating one of the keys partially projected from the holder.

50 Fig. 2 is a longitudinal sectional view through the holder with the keys removed.

Fig. 3 is an end view, parts being broken away and shown in section.

55 Referring to the drawings by characters of reference the holder includes a pair of side plates 10 and 11 which are of substan-

tially identical configuration and which are preferably cut from a single strip of material bent medially upon themselves to provide a bight portion 12 which connects the 60 same at one end. The material from which the plates are constructed is sufficiently resilient to permit of a limited relative swinging movement of said plates with respect to each other so that the free ends may be 65 separated or brought together. The free ends 13 of said plates 10 and 11 are of a substantially circular formation and are provided with the shank portions 14 of reduced elongated formation whereby the 70 plates substantially conform to the shape of the keys K which they accommodate. In order to facilitate the association of the keys with the holder and to allow for their removal and substitution while at the same 75 time permitting of a swinging movement of the keys to expose the shanks from the holder for use, a screw 15 is employed which is passed through an opening 16 in one of the free ends 13 of one of the plates and 80 said screw is provided with a reduced threaded extremity 17 which is engaged in the threaded opening 18 in the free end of the opposite plate. The openings O in the head of the keys K receive the screw shank 85 15 and the kerfed head 19 of the screw serves to limit outward swinging movement of the plate 11 with respect to the plate 10. Preferably a spring washer 20 is interposed between the keys and the plate 11 so as to 90 frictionally bind the keys against the plate 10 whereby the same are held frictionally against casual swinging movement from their adjusted positions. In order to facilitate the engagement of the finger with the 95 key shanks when housed within the holder, the shanks 14 of the plates are provided with notches 21 on one side thereof. In order to provide means for attaching the holder to a chain or key ring if desired 100 an eye member 22 is carried by the bight portion 12 of the holder.

From the foregoing it will thus be seen that a highly attractive and efficient form of holder has been devised for keys of the 105 general type illustrated, which holder facilitates the use of the keys when desired and the housing of the same when not in use.

I claim:

1. A key holder comprising a pair of side 110 plates each having a substantially circular end portion and a shank portion conforming

- generally to the shape of the keys to be held thereby, a resilient integral bridging connection between the ends of the shank portions of said plates and means extending 5 through the opposite free ends of the plates and insertable through the apertures in the keys whereby to frictionally clamp the keys between the plates for swinging movement of the same from a normally covered or 10 housed position between the plate to a position for exposing the shanks of said keys.
2. A key holder including a pair of side plates, each having a substantially circular end portion and a shank portion conform- ing generally to the shape of the keys to be held thereby, a bridging piece integrally connecting the ends of the shank portions, a connecting device coupling the circular ends of the plates, and adapted to pass through the eyes of keys in the holder, and 20 a resilient expandable member around said connecting device for frictionally retarding the swinging movement of the keys.
3. A device of the class set forth in claim 2 wherein the connecting device comprises a 25 screw and the expandable member is a spring washer encircling the screw.

ALFRED A. O. SEELER.
